COMBINATION CIGARETTE CASE AND LIGHTER

Filed Jan. 19, 1929

INVENTOR:
Joseph E. Barnes,
BY *Chas. Willard*
ATTORNEY.

UNITED STATES PATENT OFFICE

JOSEPH E. BARNES, OF CHICAGO, ILLINOIS

COMBINATION CIGARETTE CASE AND LIGHTER

Application filed January 19, 1929. Serial No. 333,641.

The present invention relates to cigarette cases and lighting devices therefor, and aims to provide a novel and unique combination of cigarette case with lighting mechanism enclosed therein in such a way as to operate automatically to provide a light for igniting a cigarette ready for use.

One of the primary objects of the invention is to devise a construction of this character in which the lighting mechanism is adapted to be operated automatically by spring tension produced by relative movement of the cigarette case sections, and said spring tension being set in operation to effect operation of a lighting mechanism at a certain interval of the relative movement between the case sections, as for example at the beginning of the closing movement of the case.

Accordingly, I have devised a combination cigarette case and lighter construction in which the spring tension created for operating the lighting mechanism is produced by the relative movement of the case sections, and the operation of the lighting mechanism is restrained by means of a detent element until the beginning of the closing movement of the case sections, when this detent element is automatically released to permit the operation of the lighter mechanism for igniting purposes.

With the foregoing general objects in view, as well as various minor objects as will appear in the course of the detailed description, the invention will now be described by reference to the accompanying drawing illustrating one of the preferred forms of embodiment of the same, after which those features deemed to be novel will be set forth and claimed.

40 In the drawing—

Figure 1 is a plan view showing a combination cigarette case and lighter embodying the present invention, and in open position;

45 Figure 2 is an end edge view of the same; Figures 3, 4 and 5 are enlarged detail sectional views, representing sections taken on the lines III—III, IV—IV and V—V, respectively of Figure 1, but Figure 5 showing the device in closed position; and

Figure 6 is an enlarged detail view of the wick-holder construction.

Referring now to the drawing in detail, this illustrates a cigarette case comprising the usual folding sections 8 connected by a hinge structure 9, the interior of the cases being provided with space for cigarettes 10 and any preferred form of retaining means such as linings or pockets 11 as shown in Figure 1.

In the present construction, the lighting mechanism comprises a compact form of receptacle or container 12 for providing a supply of ignitable liquid such as benzene, which is fed into igniting position by means of a wick element 14 the exposed end of which is embraced by a suitable holder 15 screw-fitted into a nipple 16 communicating with the receptacle 12.

The wick is exposed in position opposite to the igniter or spark-emitting device which comprises a piece of pyrophoric material 18 maintained by any suitable form of holder 20 in engagement with a striker wheel 22 connected with or formed as a part of a cog wheel 23 rotatably mounted upon a post or stud 24 as shown in Figures 1, 2 and 5. All the parts of the lighting mechanism are compactly located alongside the hinge structure 9 and separated from the pockets or spaces for the cigarettes 10 by suitable flanges 25.

The cog wheel or gears 23 is meshed with a short gear segment 26 pivotally connected, as at 27 to one end of a leaf spring element 28 which is pivoted intermediate its end, as at 29 to a stud or post projecting up from one face of the receptacle 12. At the opposite end of the leaf spring element 28, it is provided with a swivel connection, as indicated at 30 with a short link element 31 having a bowed portion 31' for projecting past the hinge structure 9, and for the purpose of making pivotal connection, as indicated at 32 with a fixed lug or bracket 34 at the opposite side of the hinge 9 from the spring 28.

The construction just described is adapted, by the closing movement of the sections 8 of the cigarette case to move the spring element 28 and the gear segment 26 into the position illustrated in Figure 1. In the mean-

time the cog wheel or gear 23 has been idly rotated in engagement with a pawl or detent element 36 which is pivoted upon a stud 37 and held by a suitable spring element 38 with the tooth of the detent in engagement with the wheel 23. Now as the sections 8 of the case are opened, the wheel 23 will be held against rotation by the detent element 36, hence producing a tension in the spring leaf 28 until said detent is released. This release is brought about by a shoulder 39 forming a part of the hinge structure 9 and engaging one end of the detent and operating in the initial part of the closing movement of the sections 8 to push the detent out of engagement with the wheel 23. By this means, the spring 28 is released, and operates through the segment 26 to impart a quick rotative movement to the wheel 23 and striker 22, thereby producing the usual spark from the material 18 to ignite the wick 14 which is located in the path of the spark. The construction is such that after the detent 36 has been thus operated, it is free to ride over the shoulder 39 during the remainder of the closing movement of the case, the spring 28 coming to rest against a limiting stop 40.

This closing movement also brings a cap element 41 into hooded relation to the wick 14 for extinguishing the flame after each use of the devise.

It will thus be apparent that I have devised a very neat, simple and compact construction for carrying out all the desired objects of the invention. There are no unnecessary parts for any waste of space, and the igniting mechanism is entirely automatic in its operation. It is furthermore apparent that the igniting or sparking operation takes place only after the case has been entirely opened, and after the beginning of the closing movement of the case, and not before the flame is needed; in this position also the position of the case sections is such as to shield the use of the flame and prevent its being accidentally extinguished by any air currents. Moreover, the spring member 28 is left free from any tension or strain except in the open position of the case, when it is ready for action upon the release of the detent member, as will be readily understood in the light of the foregoing description.

A filling cap 42 is provided as is usual in such lighting devices, to permit replenishment of the supply of liquid into the receptacle 12.

While I have shown and described what I now regard as the preferred form of construction for embodying my improvements, I desire to reserve the right to make all such changes or modifications as may fairly fall within the scope of the appended claims.

Having thus described my invention, what I claim and desire to secure by Letters Patent is:

1. A combination cigarette case and lighter comprising hingedly connected case sections, a lighter mechanism enclosed between said sections and including a spark-emitting device, and means actuated by the initial closing movement of the sections for operating said device to produce a spark. 70

2. A combination cigarette case and lighter comprising hingedly connected case sections, a lighter mechanism enclosed between 75 said sections and including a spark-emitting device, a detent element acting to restrain operation of said device, and means actuated by the initial closing movement of said case sections to release said detent element and 80 permit operation of said device to produce a spark.

3. A combination cigarette case and lighter comprising hingedly connected case sections, a lighter mechanism enclosed between 85 said sections and including a spring-actuated spark-emitting device, means for tensioning said device in response to relative movement of said case sections, and a detent element acting to hold said device under tension and 90 operated by the initial closing movement of the sections to release the device to produce a spark.

4. A combination cigarette case and lighter comprising hingedly connected case sections, a lighter mechanism enclosed between 95 said sections comprising a rotary spark producing element, a gear and segment for actuating said element, a spring operatively connected with said segment and adapted to 100 be placed under tension by relative movement of the case sections, and a detent element restraining operation of said rotary element until the beginning of the closing movement of the sections and released by 105 said closing movement to permit operative movement of said rotary element in response to the action of said spring.

In witness whereof I hereunto affix my signature.

JOSEPH E. BARNES.
